Primary Examiner — Catherine A Tuttle(74) *Attorney, Agent, or Firm* — Wolf, Greenfield & Sacks, P.C.(57) **CLAIM**

The ornamental design for a dispensing container, as shown and described.

DESCRIPTION

FIG. 1 is a top and right side perspective view of a dispensing container showing our new design; FIG. 2 is a right side elevational view thereof; FIG. 3 is a left side elevational view thereof; FIG. 4 is a rear elevational view thereof; FIG. 5 is a front elevational view thereof; FIG. 6 is a top plan view thereof; and, FIG. 7 is a bottom plan view thereof.

The broken lines illustrate portions of the dispensing container that form no part of the claimed design. The appearance of any portion of the dispensing container between the break lines seen in FIGS. 1-5 forms no part of the claimed design.
